W. F. SHAW, OF BOSTON, MASSACHUSETTS.

Letters Patent No. 87,209, dated February 23, 1869.

IMPROVED ADJUSTABLE CURTAIN-WEIGHT.

The Schedule referred to in these Letters Patent and making part of the same.

To all whom it may concern:

Be it known that I, W. F. SHAW, of Boston, in the county of Suffolk, and Commonwealth of Massachusetts, have invented a new and useful Adjustable Curtain-Weight; and I hereby declare the following to be a full, clear, and exact description thereof, which will enable others to make and use my invention, reference being had to the accompanying drawings, forming part of this specification, in which is shown a vertical section of my improvement, with a portion of the string represented attached.

My invention relates to weights connected with the rollers of curtains, and such articles, by a string, in order to hold the same suspended at any point to which the curtain may be lowered.

The purpose of my invention will be illustrated by the following remarks.

Weights, which will hold curtains at any point, when the same are new, will often prove too heavy when the roller has been used sufficiently long to run easier than at first, and, when this is the case, the weight will wind up the curtain, even when the same is drawn down so as to cover the whole window.

It is, moreover, often the case, that, when curtains are set up, it is found that the weights are not adjusted to the curtain, and so prevent the proper operation of the same.

They are often too heavy or too light.

With the tubular spring-roll curtains, now in general use, the accurate adjustment of the weight or spring is effected so as to require no change, at least for a time; but my invention relates to that kind of curtain in which the weight is attached to a string, and the string winds up on the roller, upon which the curtain is also wound.

a shows a head, with a hole therein to receive the string *b*, which is knotted on the inside to keep it in place.

This head has a screw, *c*, fitting the screw *d* in the cap *e*.

To this cap *e* is attached the rubber bulb *f*, in which is placed any substance, like shot, to act as a weight.

It will be seen that the head *a* can be unscrewed so as to open the bulb, and thus allow an addition to, or a diminution of the weighting-substance, so that the weight can be accurately adjusted to the weight of the curtain.

Sand can be employed instead of shot.

When the head is unscrewed there is no inconvenience, because the string is attached to the head.

The rubber of the bulb will prevent the weight breaking the glass, if it should swing against the same.

When the curtain has worn enough to run so easily that the weight will hold up the curtain, even when drawn down at full length, and, in consequence, the curtain cannot be kept so as to cover the window, unless the weight is so arranged as not to draw on the roller, then, by removing the head and taking out a portion of the weighting-substance, the perfect operation of the weight and roller can be secured.

What I claim as my invention, and desire to secure by Letters Patent, is—

The adjustable curtain-weight, consisting of the rubber bulb *f*, or its equivalent, screw *c*, screw *d*, cap *e*, and cord *b*, constructed substantially as and for the purpose specified.

W. F. SHAW.
